No. 794,260.

PATENTED JULY 11, 1905.

T. H. SYMINGTON.
DUST GUARD FOR RAILWAY JOURNAL BOXES.
APPLICATION FILED JULY 18, 1904.

UNITED STATES PATENT OFFICE.

THOMAS H. SYMINGTON, OF BALTIMORE, MARYLAND, ASSIGNOR TO
T. H. SYMINGTON COMPANY OF DELAWARE.

DUST-GUARD FOR RAILWAY JOURNAL-BOXES.

SPECIFICATION forming part of Letters Patent No. 794,260, dated July 11, 1905.

Application filed July 18, 1904. Serial No. 217,119.

To all whom it may concern:

Be it known that I, THOMAS H. SYMINGTON, a citizen of the United States of America, and a resident of 706 St. Paul street, city of Baltimore, and State of Maryland, have invented 5 certain new and useful Improvements in Dust-Guards for Railway Journal-Boxes, of which the following is a specification.

My invention relates to certain new and useful improvements in dust-guards for railway journal-boxes.

The object of my invention is to cheapen the cost of constructing both journal-boxes and dust-guards and make the guard more perfectly prevent the entrance of dust to the box than has heretofore been possible.

The subject-matter of this application is shown and claimed broadly in my companion application, Serial No. 227,176, filed October 20 3, 1904.

My invention comprises certain combination of parts, the preferred form of which will be first specifically described and the invention then pointed out in the claims.

Referring to the drawings, wherein the same part is designated by the same reference-numeral wherever it occurs, Figure 1 is a longitudinal sectional view of the rear part of the journal-box provided with my improved 25 guard. Fig. 2 is a sectional view similar to Fig. 1, taken at right angle to Fig. 1. Fig. 3 is a view of the back of a journal-box provided with my dust-guard.

1 designates a journal-box of any desired 35 form. This box is provided at its rear with an opening 2, through which passes the axle of the car. Around opening 2 I form a raised surface 3, the face of which is preferably machined and forms the bearing-face against 40 which the dust-guard is pressed. The opening 2 is larger than the axle, as is customary.

4 designates a ring, which has an opening 5 therein of practically the diameter of the axle, the opening 5 being slightly greater 45 than the diameter of the axle in order that the axle may turn independently of the ring.

6 designates a pair of springs, each of which is preferably bent into a pair of coils 7, as is

best shown in Fig. 3, and these coils are connected together by a loop 8. The free ends 50 9 of these springs are bent outward at an angle to each other and are adapted to enter the openings 10 in the journal-box, which are cored or bored in the walls of the box in lines which diverge from each other, so that when 55 the ends of the springs are compressed and inserted in the diverging holes they will hold themselves in place by their own elasticity. The openings 10 are located in such a position that the loops 8 of the springs when they are 60 in position press against the rear face of the dust-guard ring, holding the ring against the surface 3 on the box. It will be seen that by this construction the necessity for a dust-guard well is entirely done away with, cheapening 65 the cost of manufacturing a journal-box, and as the guard consists merely of a single metal ring and two springs the cost of constructing the guard is materially lessened.

While I have described what I believe to 70 be the preferred form of my invention, I desire to have it understood that many changes may be made in the form, construction, and arrangement of parts without departing from the spirit of my invention. 75

Having thus described my invention, what I claim, and desire to be secured by Letters Patent, is—

1. A journal-box provided with an opening 80 in its rear end through which the axle projects into the box, a dust-guard ring encircling the axle outside the box, and a spring bent into a pair of coils connected by a loop, the spring being secured to the box by its ends engaging the box and the loop resting 85 against the ring whereby the ring is held against the box.

2. A journal-box provided with an opening 90 in its rear end through which the axle projects into the box, a dust-guard ring encircling the axle outside the box, and a coil-spring bent into a pair of coils connected by a loop, the free ends of the spring diverging from each other, and adapted to enter diverging recesses in the side wall of the box, the 95 ends of the spring being held in the recesses

by their own elasticity, the loop of the spring resting against the ring whereby the ring is held against the box.

3. A journal-box provided with an opening 5 in its rear end through which the axle projects into the box, a dust-guard ring encircling the axle outside the box, a pair of springs, each spring being bent into a pair of coils connected by a loop, the springs being secured 10 to the sides of the box by their ends engaging the box and the loops resting against the ring whereby the ring is held against the box.

4. A journal-box provided with an opening 15 in its rear end through which the axle projects into the box, a dust-guard ring encircling the axle outside the box, a pair of springs,

each spring being bent into a pair of coils connected by a loop, the free ends of each of the springs diverging from each other, and adapted to enter diverging recesses in the 20 side walls of the box, the ends of each of the springs being held in the recesses by their own elasticity, the loops of the springs resting against the ring whereby the ring is held against the box.

Signed by me at Baltimore, Maryland, this 25
2d day of July, 1904.

THOMAS H. SYMINGTON.

Witnesses:

E. JOHN NICHOLS,
T. BAYARD WILLIAMS.
